UNITED STATES PATENT OFFICE.

ALFRED H. KIDNEY, OF NEW YORK, N. Y.

MEANS FOR EXHAUSTING AND CONDENSING FURNACE-FUMES.

No. 903,099.

Specification of Letters Patent.

Patented Nov. 3, 1908.

Application filed January 26, 1907. Serial No. 354,217.

To all whom it may concern:

Be it known that I, ALFRED H. KIDNEY, a citizen of the United States, residing at New York city, in the county of New York and State of New York, have invented certain new and useful Improvements in Means for Exhausting and Condensing Furnace-Fumes; and I do declare the following to be a full, clear, and exact description of the invention, such as will enable others skilled in the art to which it appertains to make and use the same, reference being had to the accompanying drawings, and to the letters and figures of reference marked thereon, which 10 form a part of this specification.

This invention relates to improvements in means for exhausting furnace hearths or chambers, of volatile products or fumes generated therein, whereby the said products or 20 fumes are drawn or forced into condensers or flues connected therewith, and in which these products are condensed and precipitated.

The means heretofore employed to perform this function, involves direct exhaustion from or through the furnace, by means of a blower, necessitating the placing of the blower about two hundred feet from the furnace outlet to the suction inlet of the blower. 30 From the pressure outlet of the blower is another length of flue leading to the interior of the condenser, the blower being in an intermediate obstructive position. The blower is thus remotely placed from the hot inflowing fumes and gases, in order that their temperature may be greatly reduced in their long passage, to obviate corrosion by metallic fumes and undue expansion of the working parts of the blower. The said means 35 heretofore employed for the purpose specified, has not proven practically or commercially successful, for the reason that condensation and precipitation occur extensively in the long suction flue, the precipitates being dropped within, with no practical facilities for their recovery. The attempt to remove precipitates so deposited, by sufficiently increased suction for the purpose, involves excessive exhaust of the furnace 45 hearth, and consequent replacement by cold air whereby the formation of volatile products is interrupted.

The object of my present invention is to

exhaust furnace hearths or chambers of their volatile, condensable metallic fumes or gases 55 generated therein, by drawing the same out through short free way flues, into connecting condensers, whereby they are incidentally rapidly cooled, precipitated and carried forward to a point or points provided for their 60 easy recovery, without personal contact, thus obviating deleterious effects and loss of values by handling the light dry product. This I accomplish by the application of a regulated cold air blast to the interior of 65 condensing flues (preferably of tubular shape and uniform diameter) in such a manner as to create positive and direct air currents through the condensing flues into terminal sections having filtering devices, 70 through which air can pass and whereby precipitates are arrested.

Having briefly outlined my improved construction as well as the function it is intended to perform, I will proceed to describe the same in detail reference being made to the accompanying drawing in which is illustrated an embodiment thereof.

In this drawing, Figure 1 is a top plan view of my improved apparatus. Fig. 2 is 80 a central longitudinal section of the same, parts being shown in elevation. Fig. 3 is a cross section taken on the line 3—3 Fig. 2. Fig. 4 is a central vertical section through the terminal portion of the apparatus provided with filtering apparatus above and a receptacle below for receiving the condensed products, the parts being shown on a greatly enlarged scale. Fig. 5 is a fragmentary longitudinal section of the condensing flue 90 showing a device for removing the condensed products from the flue.

The same reference characters indicate the same parts in all the views.

Let the numeral 5 designate each of two 95 fire boxes, and 6 revolving furnaces of ordinary construction, in which the ores or other material to be treated are subjected to the action of the desired degree of heat which is supplied by the fire boxes. The material to 100 be treated may be fed to these furnaces in any suitable manner. As nothing is claimed in this application on the special construction of furnace, the feed mechanism is not illustrated in detail. The material, however, is delivered to the smaller extremities

of the rotary furnaces from hoppers 7 and is caused to travel toward the fire boxes 5, thus necessitating that provision be made for discharging the ore or tailings as the case may be at the larger extremity of the furnace. This application, however, relates only to the means for exhausting and condensing the fumes generated in these furnaces. It is well known that in furnaces of this character, a material proportion of the values is necessarily volatilized and formed into fumes by the action of the degree of heat necessary to properly treat the ores. These fumes when condensed are in the form of metallic chlorides or other salts.

The revolving furnaces 6 are journaled at one extremity in the walls of the fire boxes 5 and at the other extremity in structures 8 upon which the hoppers 7 are mounted. These structures 8 connect the revolving furnaces with branch flues 9 which form angles of approximately thirty degrees with the condensing flue 10 with which the branch flues communicate. These branch flues 9 communicate with the main condensing flue at a point forward of its rear extremity. In the rear of the rear extremity of the condensing flue is located a blower or air forcing apparatus 12 which communicates with the rear extremity of the condensing flue, by a discharge nozzle 13. At a suitable point forward of the branch flues 9, the condensing flue is provided with an open portion 14 which as shown in the drawing is provided with elongated slots 3^a through which the condensed fumes may pass into a hopper 15 mounted above a water tank 16. The discharge extremity of this hopper is normally closed by a valve 17 carried by an arm 18 pivotally mounted at 19. The extremity of this arm opposite the pivot may be supported in any suitable manner for closing the valve 17. As shown in the drawing a removable device 20 supports the valve arm in the upper position or position corresponding with the closed position of the valve. Forward of the discharge portion of the condensing flue, is located the terminal structure 21, into which protrudes the forward extremity of the said flue. The upper part of this structure consists of a filter 22 composed of filtering material 23 supported by slats or bars 24 arranged both interiorly and exteriorly. This filter is of such construction that the air and non-condensable gases are allowed to pass upwardly therethrough into a surrounding stack 25. The lower part of the terminal structure is provided with a hopper 26 normally closed by a valve 27 carried by an arm 28 pivoted at 29 and suitably supported at the extremity opposite the pivot by a removable pin 30. When it is desired to discharge the contents of the hopper 26, the valve may be

lowered to the dotted line position in Fig. 4. The terminal structure between the filter and the hopper is provided with a portion 31 forming a sort of grate with elongated openings whereby the condensable products are allowed to pass into the hopper 26. The forward extremity of the chamber between the hopper and filter, is closed by a head 33 normally held in the position shown in Fig. 4 by coil springs 34. This head may yield in response to interior pressure but as soon as this pressure is removed, the head will return to its normal position, carrying with it any condensed products that may be in its path, whereby these products are carried into the hopper.

In order to remove the condensed products from the condensing flue, I employ a sweeping or cleaning device 35 which may be provided with segmental parts 36 adapted to engage the inside of the flue. As shown in the drawing these parts 36 are staggered both longitudinally and transversely. This arrangement of the segmental parts, permits the fumes to circulate around the cleaning or sweeping device. However, in order to further facilitate the uninterrupted passage of the air and gases through the flue, the latter is preferably made hollow (see Fig. 5) and provided with openings 37 to permit the passage of gas and air. Hence no matter where this cleaning or sweeping device may be located in the condensing flue, it will not interfere with the proper performance of the function of the exhausting apparatus.

Connected with the opposite extremities of this sweeping device, are metal cables 38 leading forwardly and rearwardly to winding drums or windlasses 39, to permit the operation of the sweeping device from the exterior of the flue, and without subjecting the operators to the inconvenience of breathing the fumes or gases generated in the furnace. The condensing flue may be made as tight as desired.

From the foregoing description the use and operation of my improved fume-exhausting and condensing apparatus will be readily understood. Assuming that the furnaces 6 are in use and that the material passing therethrough is subjected to the necessary degree of heat to volatilize a portion of the said material, the forcing of air from the atmosphere through the condensing flue 10, will exhaust the furnaces of the said fumes, cause the latter to enter the condensing flue and pass forwardly therein. The regulated cold air from the blower not only serves to exhaust the fumes from the furnaces, but also cools the latter and greatly facilitates the condensing process within the flue. The force, however, of the air current produced by the blower, will carry the greater portion of the condensed fumes, into

the terminal structure. However, the residue or remaining portion of the condensed fumes may be readily removed from the condensing flue by the operation of the sweeping or cleaning device 35 which may be moved forwardly in the flue, whereby the condensed products are discharged into the hoppers 15 and 26, and finally delivered to the water tanks 16 and 40. The tank 40 is located in a chamber 41 of the terminal structure, directly below the mouth of the hopper 26 controlled by the valve 27 as heretofore explained. This chamber 41 is provided with a door 42 which may be opened for the purpose of removing the tank 40, when for any reason it may be desirable to remove the condensed products therefrom.

By the use of a straight condensing flue of uniform interior diameter, there is no impediment to the passage of fumes and gases. At the same time it becomes practicable to employ the sweeping or cleaning apparatus for removing these condensed products from the flue to the points or places of discharge.

By the introduction of cold air into the condensing flue, I obtain rapid cooling and precipitation of the condensable metallic fumes or gases. Moreover this cooling or condensation of the fumes is effected within flues of less length, than those required in apparatus heretofore employed.

The grated openings 14 or 31 as the case may be, form supports for the cleaning or sweeping device as the latter is moved back and forth within the condensing flue and the terminal structure. If it were not for these gratings the sweeping device would have a tendency to sag downwardly within the openings which would seriously interfere with the proper performance of its function.

Having thus described my invention, what I claim is:

1. In apparatus of the class described, the combination with a furnace, of a condensing flue in communication therewith, said flue consisting of a conduit, means for introducing cold air under pressure to the condensing flue in the rear of the point where the latter communicates with the furnace, the condensing flue terminating in a filtering device and being provided with a normally closed outlet for the condensed products.

2. In apparatus of the class described, the combination with a furnace, of a condensing flue in communication therewith consisting of a single straight conduit, means for introducing cold air under pressure, to the condensing flue in the rear of the point where the latter communicates with the furnace, the condensing flue being provided with a normally closed outlet for the condensed products.

3. The combination with a furnace, of a condensing flue communicating with the

furnace intermediate the extremities of the flue, said condensing flue consisting of a single straight conduit and arranged parallel to the furnace, means for introducing cold air under pressure to the condensing flue in the rear of the point where the latter communicates with the furnace, and a terminal structure into which the forward extremity of the condensing flue protrudes, the said structure being provided with a filter interposed between the discharge extremity of the condensing flue and the stack, the lower part of the terminal structure being provided with a hopper adapted to receive the condensed products, the mouth of the hopper being normally closed for the purpose set forth.

4. The combination with a furnace, of a condensing flue communicating with the furnace, means for introducing air under pressure to the flue in the rear of its communication with the furnace, a sweeping or cleaning device located within the condensing flue, and exterior means connected with the said device for moving the same back and forth within the flue.

5. The combination with a furnace, of a condensing flue, means for exhausting the fumes from the furnace and causing them to enter the condensing flue, a sweeping or cleaning device located in the flue, and means connected therewith and adapted to be operated from the outside of the flue for manipulating the said sweeping device, substantially as described.

6. The combination with a furnace, of a condensing flue in communication with the furnace, means for exhausting the fumes from the furnace and causing them to enter the condensing flue, the latter being provided with a grated opening in its lower portion adapted to allow the fumes to escape, and a sweeping or cleaning device located within the flue and adapted to be supported by the grated portion of the flue while passing the latter for the purpose set forth.

7. The combination with a furnace, of a condensing flue communicating with the furnace, means for introducing air under pressure to the flue in the rear of its communication with the furnace, a sweeping or cleaning device located within the condensing flue, exterior means connected with said device for moving the same back and forth within the flue, and means located in the same line with the flue in the rear of its communication with the furnace for storing the cleaning apparatus when not in use.

8. The combination with a furnace, of a condensing flue, means for exhausting the fumes from the furnace and causing them to enter the condensing flue, a sweeping or cleaning device for the flue, means connect-

ed therewith and adapted to be operated from the outside of the flue for manipulating the said sweeping device, and a conduit located in the same line with the flue in the rear of its communication with the furnace for storing said cleaning device when not in use.

In testimony whereof I affix my signature in presence of two witnesses.

ALFRED H. KIDNEY.
